TRANSMISSION TOWER

Henry Dreyfuss, South Pasadena, Calif., assignor to
Southern California Edison Company, Los Angeles,
Calif., a corporation of California

Filed Oct. 12, 1967, Ser. No. 8,981

Term of patent 14 years

(Cl. D26—12)

FIGURE 1 is a front elevation of the power transmission tower embodying my novel design.

FIGURE 2 is a side elevation thereof.

FIGURE 3 is an enlarged view, taken substantially on the line 3—3 of FIGURE 1.

I claim:

The ornamental design for a transmission tower, substantially as shown and described.
